CLAIM

The ornamental design for a container for bottles, as shown and described.

DESCRIPTION

FIG. 1 is a front and top side perspective view of a container for bottles showing my new design;

FIG. 2 is a rear and bottom side perspective view thereof;

FIG. 3 is a front elevation thereof, the rear side elevation is similar to the front elevation shown;

FIG. 4 is a bottom plan view thereof;

FIG. 5 is a left side elevation thereof, the right side elevation is similar to the left side elevation shown; and

FIG. 6 is a sectional view taken at line 6—6 of FIG. 1.
